UNITED STATES PATENT OFFICE.

GEORGE H. BARDSLEY, OF PHILADELPHIA, PENNSYLVANIA.

NOZZLE-WAGON.

No. 840,287.

Specification of Letters Patent.

Patented Jan. 1, 1907.

Application filed June 29, 1905. Serial No. 267,541.

To all whom it may concern:

Be it known that I, GEORGE H. BARDSLEY, a citizen of the United States, residing at Philadelphia, county of Philadelphia, and 5 State of Pennsylvania, have invented a certain new and useful Improvement in Nozzle-Wagons, of which the following is a specification.

My invention relates to a new and useful improvement in nozzle-wagons, and has for its object to provide a wagon supporting a manifold to which the hose is connected, and to said manifold is connected one or more universally-swiveled nozzles for the purpose 15 of directing the stream of water to any portion of the burning building.

A further object is to provide means for making the wagon immovable against the pressure of the water.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a side elevation of my improved wagon; Fig. 2, a section taken on the line 2 2 of Fig. 1.

In large cities the fire departments are now installing high-pressure stations and mains by which large streams of water under great pressure can be thrown upon the fire; but it has been found that in throwing a three and 35 one-half inch stream—for instance, under a four-hundred-pound pressure—it is almost impossible for enough men to get a hold upon the nozzle to hold the same and direct the stream with any degree of accuracy, as I have found by experience that twenty men 40 could not hold the nozzle from which a three and one-half inch stream issued. Therefore I invented the nozzle-wagon herein shown, which consists of a platform A, mounted 45 upon suitable trucks, and secured to this platform is a manifold or pipe B, which is connected by the connections C at one or both ends to the supply-hose. Projecting 50 from opposite sides of the pipe or manifold 55 are the feet or webs B' to hold or secure the pipe or manifold to the platform A. It is

found in practice that the best results are obtained by having these webs oppositely opposed with a series at each end and one or more series intermediate the length thereof. 60 The advantages of the webs further lie in the fact that they hold the manifold against displacement when streams are being directed laterally of the manifold. Extending upward from this manifold is one or more outlets D, which are controlled by a valve E, and to the upper end of these outlets are connected a universally - swiveled nozzle F. This universal nozzle is already patented and upon the market, and therefore does not apply to my invention, as I reserve the right to use any form of universally-swiveled nozzle that I may desire. In order to prevent the wagon from moving under the pressure of the stream, any suitable means can be employed 70 for locking the wheels against rotation, the means shown in the drawings consisting of bars G slidably mounted to the platform A, and the outer end of each of the bars is forked, so that when the bars are slid outward laterally they will engage one of the spokes of the wheel and lock the wheels against rotation. Pins H may be used passing downward through the platform and also through holes formed in the bars G to prevent 80 the bars G from retracting through vibration or otherwise. In order to prevent the front truck from turning upon the fifth-wheel, pins I may pass downward through holes formed through the two sections of the 85 fifth-wheel, thus holding the two sections immovable relative to one another. Of course it is obvious that there are various ways in which both the wheels and the fifth-wheel could be locked. 90

In order to give the wagon still more stability, I provide the movable braces J, which consist of rods pointed at their outer ends, to the platform A. These rods normally lie along the edge of the platform, but may be 100 swung outward so as to come in contact with the ground and stand at an angle relative to the wagon, as shown in Fig. 2, bracing the wagon laterally. Thus it will be seen that by means of this wagon a number of nozzles 105 can be utilized to throw a large amount of water upon the fire, and one man can operate each nozzle easily and quickly, and the water can be thrown to any spot desired with great accuracy. 110

In the drawings I have shown the wagon equipped with two nozzles, two smaller and

two larger ones, and in the case of the smaller nozzles they will not be so high but what a man standing upon the platform can easily operate the nozzles by directly taking hold 5 of the same; but in case of the larger nozzles, if desired, they could be operated mechanically—as, for instance, by the means shown upon one of the nozzles in Fig. 1, in which a cable J' is attached at its end to the 10 upper side of the nozzle and passes downward and around a drum K, and another cable L is attached at its outer end to the lower side of the nozzle and passes downward and around the drum K in the opposite direction to which the cable J passes, so that the operator by revolving the drum will wind up one cable and unwind the other, thus being able to lower or raise the nozzle without touching the same. Of course the 15 20 nozzle will be moved upon this vertical bearing by hand. It is obvious that various means could be employed for mechanically

operating the nozzles, such as a worm-gearing or otherwise.

Of course I do not wish to be limited to the exact construction here shown, as slight modifications could be made without departing from the spirit of my invention.

Having thus fully described my invention, what I claim as new and useful is—

In combination, a truck, a longitudinally-arranged reservoir thereon, hose connections projecting from the reservoir at opposite ends in order to equalize the pressure of water within the reservoir, said connections 35 projecting from the reservoir on horizontal planes.

In testimony whereof I have hereunto affixed my signature in the presence of two subscribing witnesses.

GEORGE H. BARDSLEY.
